US0D1071140S

(12) **United States Design Patent** (10) **Patent No.:** **US D1,071,140 S**
(45) **Date of Patent:** **** Apr. 15, 2025**

(54) **WOUND IRRIGATION DEVICE**

(71) Applicants: **Justin Fearn**, Manteca, CA (US);
Grant Olguin, San Ramon, CA (US)

(72) Inventors: **Justin Fearn**, Manteca, CA (US);
Grant Olguin, San Ramon, CA (US)

(**) Term: **15 Years**

(21) Appl. No.: **29/823,988**

(22) Filed: **Jan. 21, 2022**

(57) **CLAIM**

The ornamental design for a wound irrigation device as shown and described.

DESCRIPTION

FIG. 1 is a perspective front view of the wound irrigation device;

FIG. 2 is a perspective back view of the wound irrigation device of FIG. 1;

FIG. 3 is a perspective bottom view of the wound irrigation device of FIG. 1;

FIG. 4 is a top view of the wound irrigation device of FIG. 1;

FIG. 5 is a bottom view of the wound irrigation device of FIG. 1;

FIG. 6 is a back side view of the wound irrigation device of FIG. 1;

FIG. 7 is a first lateral side view of the wound irrigation device of FIG. 1;

FIG. 8 is a front side view of the wound irrigation device of FIG. 1; and,

FIG. 9 is a second lateral side view of the wound irrigation device of FIG. 1.

The broken lines in the drawings illustrate portions of the wound irrigation device which form no part of the claimed design.

1 Claim, 5 Drawing Sheets
